UNITED STATES PATENT OFFICE.

WILLIAM C. CLOW, OF VANCOUVER, WASHINGTON, ASSIGNOR OF ONE-FOURTH TO C. W. MOORE AND ONE-FOURTH TO C. A. RAMBO, OF VANCOUVER, WASHINGTON.

JEWELER'S SOLDERING-CLAMP.

No. 920,111.

Specification of Letters Patent.

Patented May 4, 1909.

Application filed April 22, 1908. Serial No. 428,691.

To all whom it may concern:

Be it known that I, WILLIAM C. CLOW, a citizen of the United States, residing at Vancouver, in the county of Clark and State of Washington, have invented a new and useful Improvement in Jewelers' Soldering-Clamps, of which the following is a specification, reference being had to the accompanying drawings.

10 My invention relates to that class of soldering clamps used by jewelers and others for holding light and frail articles in position for soldering.

15 The object of my invention is to provide a device in which the vertical holding jaws may be adjusted horizontally with respect to each other, and which jaws are asbestos lined and pivoted at their centers to permit of a grip adjustable to the form and position 20 of the object seized, and the jaw holding arms may be separated and each used as a holder of various tools. I attain these objects as well as other advantages by the mechanism, construction, combination and 25 arrangement of parts illustrated in the accompanying drawings, which form a part hereof.

Figure 1 is a front view of my device. Fig. 2 is a side view. Fig. 3 is a side view of part 30 of a single arm with holding tools inserted in the jaws. Fig. 4 is a sectional side view of one jaw with a small tool inserted in its end. Fig. 5 is a sectional side view of one asbestos lined pivoted jaw.

35 Like letters and numerals refer to like parts throughout the views.

A and B are the vertical arms of the clamp. The said arms are composed of two members as 6-6' in Fig. 2. These members are fixedly secured to each other at their lower ends and are of resilient material. Their free upper ends are set apart a suitable distance. The member 6 is continuously vertical and is provided with a notch 7 through 40 which the horizontal part of the member 6' extends in sliding engagement. The member 6' is bent at an angle in a convenient part thereof wherein a long notch 7' is provided and extends horizontally through the notch 45 7 of the member 6, when it is again bent at an angle and extends upwardly to the same height as the member 6. Each of the members 6-6' is provided with a jaw as for example 8-8'. The jaws 8-8' are pivoted upon the pins 9-9' and are within boxes

10-10' fixedly secured in a vertical position to the upper ends of the members 6-6' of the clamp arms A-B. The jaws 8-8' have recesses in their faces of suitable form and dimensions and these recesses are filled with asbestos or other substance 11, which is a non-conductor of heat. The members 6-6' are also each provided with vertical recesses 12-12' immediately behind the jaw holding boxes 10-10' each of which recesses is of a form adapting it to receive a tool such as 13-13' or 14-14'.

The arm A is provided with a split plug 15 of suitable length, having its split end slightly expanded and is pivoted on the pivot 16 at the lower end of the arm A, the opposite end of the plug being free. The arm B is provided with a tube 17 fixedly secured to the lower end of said arm at right angles to the same and of suitable form and dimensions to receive the plug 15 therein a suitable distance. In Fig. 1 a broken bar 18 is shown, a part of the same being held by the jaws of each arm. In Fig. 3 a ring 19 is shown within the grip of tools 14-14' which are placed within the receiving recesses 12-12' of one of the arms.

It will now be seen that the operation of the clamp is as follows: The arms A-B are adjusted a suitable distance apart to receive a spectacle frame or other article by sliding the plug 15 within the tube 17. The object to be soldered is then placed within the jaws of each arm after they are sprung apart and upon releasing them they hold the object as desired. The non-conducting substance upon the face of the jaws engaging the object prevents the loss of heat when the solder is applied as would be the case by a direct contact of metal with metal. Should it be desired to use one arm as a holder of auxiliary tools, the plug 15 is removed from the tube 17 and may be bent downward to facilitate grasping and handling the arm A. The two members 6-6' may then either or both be fitted with auxiliary tools to be operated with each other or singly. The arm B having the rigid tube 17 may be secured in a vise for instance with auxiliary tools in its upper end as in the case of the arm A.

105 My device is peculiar to itself with respect to all others as it has the automatically adjustable jaws and contains no set screws, thumb nuts or ratchets as many others do and the asbestos lined jaws enable the oper- 110

ator to work more satisfactorily and quicker when soldering any object.

Having thus fully described my invention, I claim:

- 5 1. A soldering clamp of the kind described, comprising an arm A, having a jaw at its upper free end, and a split plug pivoted at one end to the lower end of the arm, also an arm B of similar construction to the arm A, except in place of the split plug, it has a tube fixedly secured at one end to the lower end of said arm B at right angles thereto and of a form adapting it to receive therein, said split plug.
- 10 2. A soldering clamp of the kind described, comprising an arm A having a vertical resili-

ent member free at the upper end and pivotally secured at its lower end to the end of a split plug, also provided with a pivoted jaw upon the upper end, said jaw being faced with a material not a conductor of heat, an arm B of similar construction to arm A, except in place of the split plug, it has a tube fixedly secured at one end to the lower end of said arm B at right angles thereto and of a form adapting it to receive therein said split plug.

WILLIAM C. CLOW.
